United States Patent Office

Des. 218,989
Patented Oct. 20, 1970

218,989

SPOON OR SIMILAR ARTICLE

Jose Carlos Mario Bornancini, Porto Alegre, Brazil, assignor to Hercules S.A.-Fabrica de Talheres, Rio Grande do Sul, Brazil, a corporation of Brazil

Filed July 10, 1969, Ser. No. 18,166

Term of patent 14 years

Int. Cl. D7—03

U.S. Cl. D54—12

Fig-1

Fig-2

Fig-3

Fig-4

In the drawings:

FIG. 1 is a front view of a spoon or similar article showing my new design;

FIG. 2 is a side view of the spoon or similar article;

FIG. 3 is a back view;

FIG. 4 is a section taken on the line 4—4 of FIG. 1; and

FIG. 5 is a section taken on the line 5—5 of FIG. 1.

The side opposite that shown in FIG. 2 is a mirror image thereof.

I claim:

The ornamental design for a spoon or similar article, as shown and described.
